UNITED STATES PATENT OFFICE.

ISIDOR KRAUS, OF NEW YORK, N. Y.

DESIGN FOR A STAND.

42,762.

Specification for Design.

Patented July 9, 1912.

Application filed December 16, 1911. Serial No. 666,272. Term of patent 7 years.

To all whom it may concern:

Be it known that I, ISIDOR KRAUS, a subject of the Emperor of Austria-Hungary, residing at New York, county of New York, and State of New York, have invented a new, original, and ornamental Design for a Stand, of which the following is a specification, reference being had to the accompanying drawing, forming part thereof.

The figure is a perspective elevation of the article.

The article consists of an ornamental ash tray, from the center of which extends a hollow post, a match box secured to the top of an ornamental rod is engaged within the hollow post and fastened therein at its bot-

tom. Rotatively mounted on the said rod is an ornamental sleeve, which is provided with laterally extending arms supporting cruets for pepper, salt, and the like, and below these arms frames are arranged in form of swings to receive advertising matter.

I claim:

The ornamental design for a stand, as shown and described.

In testimony whereof, I affix my signature in the presence of witnesses.

ISIDOR KRAUS.
